UNITED STATES PATENT OFFICE.

PHILIP B. HARRISON, OF CHICAGO, ILLINOIS, ASSIGNOR TO CHICAGO RAILWAY EQUIPMENT COMPANY, OF CHICAGO, ILLINOIS, A CORPORATION OF ILLINOIS.

CORE-OVEN.

1,120,937.

Specification of Letters Patent. Patented Dec. 15, 1914.

Application filed June 28, 1913. Serial No. 776,429.

To all whom it may concern:

Be it known that I, PHILIP B. HARRISON, a citizen of the United States, residing at the city of Chicago, State of Illinois, have 5 invented a certain new and useful Improvement in Core-Ovens, of which the following is a full, clear, and exact description, such as will enable others skilled in the art to which it appertains to make and use the 10 same, reference being had to the accompanying drawings, forming part of this specification, in which—

Figure 1 is a diagrammatic side elevational view of my improved core oven. Fig. 15 2 is an enlarged vertical sectional view through the same. Fig. 3 is a plan view of one of the sections. Fig. 4 is a front elevational view showing the front casing removed.

20 This invention relates to a new and useful improvement in core ovens, the object being to construct a device of the character described which is simple, cheap and efficient.

25 Heretofore, in the production of cores for castings it has usually been the practice to bake the cores in a chamber where they will come in direct contact with the products of combustion. The result is that the cores 30 are not uniformly baked and it frequently happens that the surfaces in direct contact with the flames will be overbaked and become brittle so that corners will be broken in handling. By the use of my construction wherein steam is employed as the heating medium and the steam pipes constitute the shelves or supports on which the trays containing the cores rest, I am enabled to uniformly bake the cores throughout their 35 entire masses respectively getting rid of moisture, the cores being "baked" to the desired degree so that they are tough and can be handled without fear of breakage.

In practice, I prefer to use steam at about 45 100 pounds pressure, which will give a heat in the oven of about 210 or 215 degrees, sufficient to evaporate all moisture in the cores and bake them thoroughly. The cores are left in the oven for from 3 to 4 hours, or 50 such time as practice shows to be best suited for the particular composition of the cores being baked.

In the drawings, I have shown my improved core oven arranged as a battery, although it is obvious that any other arrange-

ment best suited to local conditions can be resorted to.

1 indicates a brick back wall, which may be the wall of a building, against the lower portion of which is arranged a channel 2. 60 3 is the front channel preferably parallel to the channel 2 and being provided with openings for the passage of suitable exhaust pipes hereinafter referred to. Channel 3 is also provided with ventilating openings 4 (see Fig. 4) which are controlled by suitable plugs or doors, not shown. Resting upon the channels 2 and 3 are upright angles 5, the front posts or angles being arranged in short sections and connected to a 65 belt rail or angle 6.

7 are top angles to which the upper ends of the posts 5 are connected, said top angles in turn being connected to the buck staves 8 between which are secured the partition walls 9. A brick arch 10 is supported upon the top angles 7 and suitable doors, not shown, close the openings in the front wall of the oven. Preferably there are upper and lower doors, but, of course, a single 70 door may be employed throughout the entire height of the oven.

The steam for the battery of ovens is taken from a header 11 and connected by a valved connection to a stand pipe 12. Midway from this stand pipe leads a pipe 13 for supplying steam to the first series of coils 14 constituting the upper shelf or support for the core trays. This upper shelf is connected by a vertical pipe 15 to the coils 16 of the second shelf and so on down to the lower series of coils 17 of the upper compartment, which latter is in turn connected by an exhaust pipe 18 to carry off the water of condensation to the discharge pipe 20, the pipe 18 extending outwardly through an opening in the channel 3 so that it may contain a valve in its length whose handle 21 is accessible from the exterior. In this manner by the valves in the supply and exhaust pipes each unit or section may be individually controlled and both the supply of steam and the discharge of the water of condensation regulated to suit requirements. The lower end of the stand pipe 12 connects to one end of a series of coils 22 constituting the upper supporting coils of the heating pipes in the lower compartment of the oven; the steam thence being conducted down through the remaining coils, the water of 110

condensation being carried off by a pipe 23 which connects with the discharge pipe 18 from the upper series of coils. By supplying steam directly to the uppermost coils of 5 a series in each oven, I am enabled to obtain a higher temperature in the upper part of the oven than is secured in the lower portion thereof, which is desirable in that some small cores may thus be more advantageously 10 baked in the lower or cooler portion of the oven. Of course, as the cores are heated and there is less condensation of the steam in the pipes, there will eventually be live steam throughout the entire series of pipes, thus 15 bringing the temperature of the oven even throughout.

Suspended from the top angles 7 are bars 24 which are connected by means of cross supports 25 on which the coils of the upper 20 and lower series rest. These bars 24 are preferably free to move slightly and constitute the only supports for the coils of pipe, thus permitting said coils of pipe to expand and contract readily as they are 25 alternately heated and cooled.

The openings 4 in the channel 3 above referred to constitute ventilating openings into which air may be introduced into the lower portions of the several chambers of 30 the oven, the hot humid air escaping through pipes 26 which lead respectively to a stack 27. There are as many ovens connected to a stack as the capacity of the stack will readily accommodate, and in order to get 35 the best results in utilizing the ventilating openings in the bottom, the doors of the ovens are preferably close fitting so that the

air drawn in at the bottom of the ovens will pass through the entire oven upwardly so as to carry off the humid hot air.

40

What I claim is:

1. A core oven comprising walls constituting a baking chamber, coils of steam pipes arranged therein for supporting core trays, and supports for said coils, said supports 45 being suspended from the upper portion of the oven whereby the coils of pipe are free to expand and contract.

2. A core oven comprising flanged members forming a chamber at the lower portion 50 of the oven, flanged uprights and connecting pieces forming a support for top and side walls, coils of pipe arranged in the baking chamber, and suspended supports for said coils of pipe which are independent of said 55 walls.

3. A battery of core ovens, each oven comprising walls constituting a baking chamber, coils of steam pipes arranged therein for supporting the core trays, supports for said 60 coils suspended from the upper portion of the oven, means for separately regulating the steam admitted into the coils of each oven, ventilator openings for letting air into the bottom portion of each oven and pipes 65 leading from the upper part of each oven to a common stack.

In testimony whereof I hereunto affix my signature in the presence of two witnesses, this 12th day of June, 1913.

PHILIP B. HARRISON.
